UNITED STATES PATENT OFFICE.

FRANKLIN P. McCARTY, OF ST. LOUIS, MISSOURI.

GAS-RANGE.

1,257,372.

Specification of Letters Patent. Patented Feb. 26, 1918.

Application filed May 19, 1917. Serial No. 169,806.

To all whom it may concern:

Be it known that I, FRANKLIN P. McCARTY, a citizen of the United States, residing at St. Louis, Missouri, have invented a certain new and useful Improvement in Gas-Ranges, of which the following is a full, clear, and exact description, such as will enable others skilled in the art to which it appertains to make and use the same.

This invention relates to gas ranges of the type now in general use in which the top burners are located between the top of the range on which the cooking utensils are placed, and a horizontally-disposed plate or partition that is arranged underneath the burners, the tops of ranges that are operated or heated by manufactured gas usually being open or of skeleton construction and the tops of ranges that are heated by natural gas usually being closed and provided with openings for the cooking utensils. When a range of the type referred to is in use the heat from the top burners which is not utilized to heat the cooking utensils, escapes into the room in which the range is located, and thus raises the temperature of the room to such a degree that it is uncomfortable for the occupants in warm weather, particularly the cook, who stands in close proximity to the top burners. Furthermore, the cost of operating such a range is out of all proportion to the degree of efficiency of the range. The above is true of both closed and open top ranges, because the top portion of a closed top range is of such design that the excess heat from the top burners can escape laterally under the lower edge of said top portion, and the skeleton form of an open top range of course permits the excess heat from the burners to escape upwardly through same.

The main object of my invention is to provide a gas range which is so constructed that the heat from the top burners will not escape into the room in which the range is located.

Another object is to provide a gas range of the kind just referred to which is so constructed that the excess heat from a top burner over which a cooking utensil or other device is arranged can be conserved and utilized to heat a cooking utensil or other object arranged at a different point on the top of the range, thereby materially reducing the cost of operating the range and increasing its degree of efficiency.

To this end I have devised a gas range equipped with top burners of any suitable type that will burn either natural or manufactured gas and provided with a closed top that extends over said burners. The top has openings in vertical alinement with the burners for receiving cooking utensils or other objects, which openings are normally closed by removable lids. Said top is provided with a skirt portion or depending flange or wall that extends downwardly to a point below the top burners, and the combustion chamber or space inclosed by said top and skirt portion is open at its lower side so as to insure a sufficient supply of air to the top burners of the range to support combustion. The heat that is generated in said space when one or more of the top burners are in use is conducted away from said space through a flue or flues of novel construction, which eliminates the possibility of the heat escaping into the room by passing downwardly under the lower edge of the skirt portion on the top of the range.

Figure 1 of the drawings is a front elevational view, partly in vertical section, of a gas range constructed in accordance with my invention.

Fig. 2 is a top plan view of said range; and

Fig. 3 is a vertical sectional view, taken on the line 3—3 of Fig. 2.

Referring to the drawings which illustrate the preferred form of my invention, A designates the top of my improved gas range, which top consists of a horizontally-disposed portion provided with openings 1 for receiving cooking utensils or other objects (not shown) and equipped with removable lids 2 that are adapted to be arranged in the openings 1 that do not contain cooking utensils, so as to form a solid top portion that extends over the top burners B of the range. The top burners B are arranged below the top A in vertical alinement with the openings 1 in the top, and the usual supply pipe or gas manifold B' is arranged at the front of the range so as to supply gas to said burners. The top A is provided with a skirt portion C formed by a depending flange or wall that projects downwardly from the top A at the four sides of same, thus producing an inclosing housing for the top burners whose underside is open to the atmosphere, as shown in

Fig. 1. The lower edge of the skirt portion C terminates at a point below the burners B, and while it is immaterial, so far as my broad idea is concerned, how the top A and skirt portion are constructed, I prefer to insulate said parts so as to prevent them from acting as heat radiators which throw off the heat that is produced in the combustion chamber or burner space that is 5 partially inclosed by said parts. In the form of my invention herein shown the top A and skirt portion C are hollow and filled with heat insulating material α , but said parts can be insulated in any other preferred manner without departing from the 10 spirit of my invention.

The heat that is generated in the combustion chamber or burner space covered by the top A and surrounded by the skirt portion C when one or more of the top burners B are in use is conducted away from said space through a discharge flue D that leads 15 to an uptake pipe D' which is preferably arranged adjacent the back of the range. It is immaterial, so far as my broad idea is concerned, how many discharge flues the 20 top portion of the range is equipped with, but I prefer to use one discharge flue D, as herein shown, of sufficient capacity to carry off all of the excess heat when all of the top 25 burners are in use. Said flue D can be constructed in various ways without departing from my invention, but it preferably consists of a passageway open on its underside, 30 as shown in Fig. 1, and provided with vertically-disposed side walls 3 that extend down into the combustion chamber and whose lower edges terminate in a horizontal plane located slightly above the horizontal 35 plane in which the lower edge of the skirt portion C terminates. Said flue can also be arranged in various ways without departing from my invention, but it is preferably arranged beneath the top A at approximately 40 the center of same and extends rearwardly from the front side of the skirt portion C to the uptake pipe D', as shown in Fig. 3. When one or more of the top burners B are in use, the cool air in the burner 45 space or combustion chamber will be forced downwardly by the ascending hot air, and consequently, will escape from the burner space into the flue D under the lower edge of the vertical side wall or walls 3 of said 50 flue, as indicated by the arrows in Fig. 1, due to the tendency of flowing air to take the path of least resistance. In other words, by equipping the range with a closed top and a discharge flue open on its underside 55 and provided with side walls that are of slightly less depth than the depending skirt portion C which surrounds the burner space, I eliminate the possibility of the heat generated in the burner space from passing 60 downwardly and outwardly under the lower edge of the skirt portion.

edge of the skirt portion, owing to the fact that the cool air which is constantly being displaced downwardly by the ascending hot air in the burner space will find an outlet when it reaches the lower edge of the side 70 walls 3 of the flue D. By arranging the discharge flue D at approximately the center of the top of the range between the two sets of top burners, I assure the escaping air and products of combustion flowing laterally 75 away from the burner, as indicated by the arrows in Fig. 2, thus eliminating cross drafts over the burners. This is only the preferred arrangement of the discharge flue D, however, as said flue could be arranged in various other ways without departing from my invention. The top wall 4 of the flue D is preferably inclined upwardly from its front end toward its rear end, as shown in Fig. 3, so as to tend to induce a circulation through said flue toward 80 the uptake pipe D'.

A gas range of the construction above described is a decided improvement on gas ranges of the type which comprise a skeleton 90 top, on account of the fact that the top portion of my range is so constructed that the heat from the top burners which is not utilized to heat the cooking utensils arranged over the burners is conducted into a discharge flue or flues that lead to an uptake pipe, instead of being discharged into the room in which the range is located. Another desirable feature of my improved range is that one burner can be used to heat two cooking 95 utensils or other objects by simply arranging two cooking utensils in the two openings 1 in the top of the stove at one side of the flue D and then lighting the burner arranged under the front opening, the excess 100 heat from said burner filling the space in which the two burners are arranged, and thus serving to heat the cooking utensil arranged in the rear opening 1. Consequently, 105 my improved range is more efficient and can be operated at a lower cost than gas ranges 110 of the type which comprise a skeleton top, because such ranges are not provided with means for conserving and utilizing the excess heat from a burner that is in use.

Having thus described my invention, what I claim, and desire to secure by Letters Patent, is:

1. A gas range provided with a closed top forming a permanent part of the stove and having a depending skirt portion, burners arranged in the combustion chamber underneath said top, and a discharge flue in said top having side walls that project downwardly into said combustion chamber, the lower edges of said side walls terminating in a higher horizontal plane than the lower edge of said skirt portion.

2. A gas range, comprising top burners arranged in a combustion chamber, a top

portion that extends over said burners, said top portion being open at its underside and provided with a depending skirt that surrounds the burners, and a discharge flue 5 open at its underside and provided with side walls that project downwardly into said combustion chamber and which terminate in a higher horizontal plane than the lower edge of the depending skirt of the top portion which surrounds the burners.

3. A gas range, comprising a combustion chamber or closed top forming a permanent or integral part of the stove and provided with openings for receiving cooking utensils 15 or other objects, the underside of said combustion chamber being open to the atmosphere, gas burners arranged in said combustion chamber, a depending skirt portion on said top for preventing the heat generated 20 in the combustion chamber from escaping laterally into the room, and a discharge flue for said heat arranged under the top in such a manner that the escaping air and products of combustion will not create cross 25 drafts over said burners, said flue being open on its underside and provided with side walls that project down into said combustion chamber and whose lower edges terminate in a higher horizontal plane than the lower edge 30 of said skirt portion.

4. A gas range, comprising an insulated top forming a permanent part of the stove and provided with a combustion chamber that is surrounded by a skirt portion on said 35 top, said top having openings for receiving cooking utensils or other objects, and a discharge flue in said top open on its underside and having side walls that project down into said combustion chamber and whose lower edges terminate in a higher horizontal plane 40

than the horizontal plane in which the lower edge of said skirt portion terminates.

5. A gas range having a closed top that is provided with a depending skirt portion which surrounds the combustion chamber, a 45 discharge flue arranged at approximately the center of said top and extending rearwardly from the front side of said skirt portion to an uptake pipe, and gas burners arranged under said top in said combustion chamber at opposite sides of said discharge flue, said discharge flue being open on its underside and provided with side walls that project down into said combustion chamber and whose lower edges terminate in a higher 50 horizontal plane than the lower edge of said skirt portion.

6. A gas range having a closed top forming a permanent part of the stove and provided with a combustion chamber that is 55 surrounded by a depending skirt portion on said top, said top and skirt portion being insulated and the top being provided with openings for receiving cooking utensils or other objects, burners inclosed by said top, 60 and a discharge flue under said top which communicates with an uptake pipe, said flue being formed by a top wall that is inclined 65 upwardly toward said uptake pipe and side walls that project down into the combustion 70 chamber and whose lower edges terminate in a higher horizontal plane than the lower edge of said skirt portion so that the heat which is generated in the combustion chamber under the top will escape into the open 75 lower side of said flue instead of passing downwardly and laterally under the lower edge of said skirt portion.

FRANKLIN P. McCARTY.
